(57) **CLAIM**

The ornamental design for the handle for cleaning machine,
as shown and described.

DESCRIPTION

FIG. 1 is a front view of a handle for cleaning machine showing my new design;

FIG. 2 is a rear view of the handle for cleaning machine of FIG. 1;

FIG. 3 is a left side view of the handle for cleaning machine of FIG. 1;

FIG. 4 is a right side view of the handle for cleaning machine of FIG. 1;

FIG. 5 is a top view of the handle for cleaning machine of FIG. 1;

FIG. 6 is a bottom view of the handle for cleaning machine of FIG. 1;

FIG. 7 is a front perspective view of the handle for cleaning machine of FIG. 1;

FIG. 8 is a rear perspective view of the handle for cleaning machine of FIG. 1;

FIG. 9 is an enlarged view of 9 marked in FIG. 3;

FIG. 10 is an enlarged view of 10 marked in FIG. 5; and,
FIG. 11 is an enlarged view of 11 marked in FIG. 6.

The broken lines shown in the drawings are for the purpose
of illustrating portions of the handle for cleaning machine
which form no part of the claimed design.

1 Claim, 11 Drawing Sheets
